CLAIM

We claim the ornamental design for a coral farm crate, as shown and described.

DESCRIPTION

FIG. 1 is a top, front, right isometric view of a coral farm crate showing our new design;

FIG. 2 is a bottom, front, right isometric view thereof;

FIG. 3 is a front view thereof (the back view being a mirror image thereof);

FIG. 4 is a right side view thereof;

FIG. 5 is a left side view thereof;

FIG. 6 is a top view thereof;

FIG. 7 is a bottom view thereof; and,

FIG. 8 is a top, front, right isometric view of the coral farm crate shown in FIGS. 1-7 including coral tiles on the top of each threaded pin.

The broken lines are included for the purpose of illustrating environmental structure and form no part of the claimed design.

The shade lines in the Figures show contour and not surface ornamentation.
